(57) **CLAIM**

The ornamental design for a synthetic resin paper, as shown and described.

DESCRIPTION

FIG. 1 is a view of the synthetic resin paper; and,
FIG. 2 is an enlarged view of FIG. 1.

The pattern shown in the claimed design is continuous and
may repeat in up, down, right and left directions. The thick-
ness of the synthetic resin paper is de minimus, i.e., it is
essentially without visible thickness.
